UNITED STATES PATENT OFFICE.

HOWARD M. SWEET, OF DETROIT, MICHIGAN.

PLOW.

1,373,537.

Specification of Letters Patent.

Patented Apr. 5, 1921.

Application filed October 15, 1917. Serial No. 196,601.

To all whom it may concern:

Be it known that I, HOWARD M. SWEET, a citizen of the United States, residing at Detroit, county of Wayne, State of Michigan, have invented a certain new and useful Improvement in Plows, and declare the following to be a full, clear, and exact description of the same, such as will enable others skilled in the art to which it pertains to make and use the same, reference being had to the accompanying drawings, which form a part of this specification.

This invention relates to plows, and its object is a plow in which the share, mold board, etc., may be set an angle to the plow beam.

In the usual hand operated plow, the plowman either holds the plow so that the landside is in a vertical plane or at an angle thereto. Under the various conditions, as is hereinafter described with the usual power operated plow such a manipulation is impossible, and by means of this invention the plow may be fixed at the angle desired.

An object of the invention, therefore, is a single and efficient arrangement of the parts to fix the position of the plow relative to the beam. The beam and plow proper being pivotally connected, means are provided to hold the plow in set position.

These and other objects and the several novel features of the invention in its preferred form are hereinafter more fully described and claimed and shown in the accompanying drawings in which—

Figure 1 is a side elevation partly in section of a plow embodying my invention.

Fig. 2 is a plan view thereof.

Fig. 3 is a rear elevation showing the plow set with the landside in a vertical plane.

Fig. 4 is a similar view showing the plow set at an angle.

Fig. 4^a shows an alternative of adjusting means.

Figs. 5, 6 and 7 are diagrams indicating the result arising from plowing with the plow portions set at various angles relative to the beam.

Similar characters refer to similar parts throughout the drawing and specification.

The beams 1 may be of any desired construction, it being essential to this invention that the beam be held from transverse movement or side twist relative to the plow.

The lower end is provided with a hub member 2 having a central aperture in a line parallel with the beam, as will be understood from the drawing. A frog 3 is bolted to the landside 4 of the plow, which is provided with a threaded lug 5 at one end and a lug 6 at the opposite end apertured to receive the end of the hub 2. When the hub is in position a bolt 7 is inserted through the central aperture, as will be understood from Fig. 1 and threaded into the lug 5 securely holding the plow and beam in pivotal relation. The landside share and mold board may be of any usual approved character, and the mold board is provided with a member 8 in which one end 9 of the turn buckle is pivotally secured. The beam 1 is likewise provided with a member 10 to which the opposite threaded member 11 of the turn buckle is pivoted. A nut 12 of the turn buckle connection may be operated to set the plow at the angle as indicated in Fig. 4, or at the angle opposite thereto, as indicated by a dotted line α or various positions within the limits of the apparatus.

Fig. 4^a is a view of the plow similar to Fig. 4 showing any alternative means for setting the landside share and mold board of the plow at an angle to the beam and consists of a threaded socket 20 pivotally secured to the mold board. A squared shaft 21 is threaded in the socket 20 and the other end of the shaft is threaded in a socket 22 pivotally secured to the bracket 10 on the plow beam. The shaft 21 is provided with right and left hand threads at each end respectively so that upon turning the shaft in one direction the mold board and landside are drawn together and rotation of the shaft 21 in the opposite direction tends to separate them.

With a plow set as shown in Fig. 3 the ground in plowing is turned as shown in Fig. 5 which is the usual position with grounds of some nature particularly sandy loam and the like. As the plow is turned at the angle indicated by the dotted line α in Fig. 4, the result is somewhat as indicated in Fig. 6, the plow cutting deeper on the landside edge than on that of the share. With the plow so set less power is required to operate the same, but with some character of grounds, particularly sod, the grass and weeds at the edges of the turned furrows soon grow up between the furrows, as indicated in the drawing and with ground

in which such condition is liable to occur, the plow should be set so that the landside undercuts after the manner in Fig. 7. By this arrangement the loose earth at the 5 turned edge *b* falls over and covers up the vegetation preventing the growth thereof between the several turned furrows.

By the pivotal arrangement of the plow beam relative to the mold board and land 10 side the latter may be set at the desired angle required by the nature of the ground to be plowed whereafter the plow will continue to turn the furrow in the desired manner without further attention on the 15 part of the operator. The desired result is secured particularly by reason of connecting the land side and mold board in a fixed angular relation and pivotally supported as a unit relative to the beam.

20 Having thus briefly described my invention, its construction and utility, what I claim and desire to secure by Letters Patent of the United States is—

1. In a plow, a plow beam, a plow share, 25 mold-board and land-side, the plow share and mold-board and land-side being secured in fixed relative position pivotally supported to the beam to swing on a horizontal axis to vary the angle of the land-side relative to the vertical, the construction permitting the positioning of the base of the land-

side on either side of a vertical plane for the purpose described, and an adjusting device for securing the unit in the desired position.

2. In a plow, a plow beam, the plow having a mold board and land side in fixed relative position and adjustable as a unit about a horizontal pivot, and means for adjusting the angle of the mold board and land side 40 relative to the beam.

3. In a plow, a plow beam having an aperture at the rear end extending parallel with the beam, a frog adapted to receive the apertured end of the beam, a bolt securing the beam and frog in pivotal relation, the land side, mold board and plow share of the plow being fixedly attached to the frog, and a turn buckle secured to the beam and mold board adapted to hold the mold board, 50 land side and share in adjustable relation with the beam.

4. In a plow, a frog, a mold board and land side secured thereto in relative fixed relation, a beam, the frog being secured to 55 the beam to swing on a horizontal axis, and an adjustable member for varying the angle of the mold board and land side relative to the vertical.

In testimony whereof I sign this specification.

HOWARD M. SWEET.
